UNITED STATES PATENT OFFICE

RAY REGINALD SHEARER, OF CLEVELAND, OHIO

DESIGN FOR A RADIOCABINET

Application filed August 14, 1931. Serial No. 40,856. Term of patent 7 years.

To all whom it may concern:

Be it known that I, RAY REGINALD SHEARER, a citizen of the United States, residing at Cleveland, in the county of Cuyahoga and State of Ohio, have invented a new, original, and ornamental Design for a Radiocabinet, of which the following is a specification, reference being had to the accompanying drawing, forming part thereof.

The drawing is a perspective view of my radio-cabinet.

I claim:

The ornamental design for a radiocabinet as shown.

RAY REGINALD SHEARER.
